UNITED STATES PATENT OFFICE.

ABRAHAM B. HARRIS, OF ETTER, VIRGINIA.

SHOESTRING-FASTENER.

SPECIFICATION forming part of Letters Patent No. 679,022, dated July 23, 1901.

Application filed March 25, 1901. Serial No. 52,852. (No model.)

To all whom it may concern:

Be it known that I, ABRAHAM B. HARRIS, a citizen of the United States, residing at Etter, in the county of Wythe and State of Virginia, have invented a new and useful Shoestring-Fastener, of which the following is a specification.

This invention relates to a shoe string or lace fastener; and the object of the same is to provide a simple and effective device of this class which will not tear out of the shoe-upper after it has been properly applied and which will serve as a convenient means for securing the string or lace extremities and overcome the necessity of tying or untying the same.

The invention consists in the construction and arrangement of the several parts, which will be more fully hereinafter described and claimed.

In the drawings, Figure 1 is a front elevation of a portion of the upper of a lace-shoe, showing the improved lace-fastener applied thereto, said fastener being disposed in duplicate on opposite sides of the opening in the upper. Fig. 2 is a similar view of a portion of an upper, showing the improved fastener in single form and on an enlarged scale. Fig. 3 is a horizontal section through the upper portion and fastener as shown by Fig. 2.

Similar numerals of reference are employed to indicate corresponding parts in the several views.

The improved fastener comprises an inner reinforcing or backing plate 1, an outer supporting-plate 2, a space-washer 3, a spring-tongue 4, and rivets 5 and 6. The plates 1 and 2 are elongated and of equal length and width, said plates when applied, respectively, against the inner and outer sides of the upper being in transverse coincidence. The outer ends of the plates 1 and 2 are secured by the rivet 6, passed therethrough and the portion of the upper between said plates and closely upset or headed over against both plates. The space-washer 3 is then placed against the inner end of the supporting-plate 2, and the inner end of the tongue 4 is disposed on the washer, and after the latter parts have been properly arranged the rivet 5 is passed therethrough and upset against the

plate 1 and the tongue end, said latter rivet being longer than the rivet 6 for obvious reasons. When the several parts are secured, as just explained, a firm engagement is produced in relation to the shoe-upper, and the pulling strain on the tongue is distributed equally over the two plates 1 and 2, and the latter having the securing devices therefor at the ends and said securing devices spaced apart a considerable distance it will be impossible for said securing devices to be pulled out or the upper torn at the points they engage therewith. Hence a reliable fastening for the improved device is provided without liability of wear or injury to the shoe or other device to which the fastener may be applied.

The tongue 4 is reduced in width toward its outer end, and the latter is flared outwardly to permit the lace to pass easily thereunder, and by spacing the tongue in relation to the plate 2 and holding the inner end on the space-washer, as shown, it is not liable to break or become worn so rapidly by constant use. It is common in fasteners embodying spring-tongues to have the latter break off at the point of integral bend with a support; but by the present mode of connecting the tongue this disadvantage is overcome.

The fastener is adapted to be used in either double or single arrangement, and when applied on opposite sides of the opening in an upper, as shown by Fig. 1, the entrances under the tongues are outermost, so that the lace extremities can be crossed alternately from one to the other and be secured, as shown. One of the fasteners may be used to answer the same purpose and both lace extremities passed under the tongue thereof, and it is also intended to apply the fastener to devices other than shoes wherever found applicable.

The improved device can be easily applied and is of a comparatively inexpensive nature.

Having thus described the invention, what is claimed as new is—

The combination with a shoe-upper, of a pair of elongated plates of equal length, a space-washer, a tongue and a pair of rivets, one of the latter being longer than the other, the plates being disposed against the inner

and outer surfaces of the upper so that their edges will be in coinciding planes, the said plates having their outer ends secured to each other and to the upper by the shorter rivet, 5 the space-washer being applied to the inner end of the outer plate with the inner end of the tongue bearing thereon, and the inner ends of both plates, the washer and the inner tongue end unitedly secured to each other 10 and to the upper by the longer rivet, the

tongue projecting longitudinally outwardly over the said outer plate.

In testimony that I claim the foregoing as my own I have hereto affixed my signature in the presence of two witnesses.

ABRAHAM B. HARRIS.
